HAT FORM

Frieda Elle, Chicago, Ill.

Application May 13, 1932, Serial No. 611,078

19 Claims. (Cl. 223—21)

My invention relates in general to hat forms. It relates more in particular to an adjustable hat form particularly adapted for use in manufacturing women's hats, although adapted to have other uses.

Women's hats are customarily manufactured on a form having substantially the shape of the hat, and to which ornaments are pinned in the process of manufacturing. These forms are usually made out of very soft wood or cork and usually last for a comparatively short time, due to the fact that they are gradually split by the pins. The forms as now used must be made in a large number of sizes, being non-adjustable, and this requires the manufacturer to carry a large number of head sizes on hand. The hat form must be made of material which will take the pins, but over the surface of which the needle will move readily so that in sewing ornaments onto the hat body there will be no possibility of attaching the stitches to the form.

The principal object of my invention is the provision of an improved hat form for the purpose described.

Another object is the provision of a hat form which can be adjusted to various sizes.

Another object is the provision of such a form which may be used for stretching hats, if desired.

Other objects and features of the invention will be apparent from a consideration of the following detailed description taken with the accompanying drawing, wherein

Fig. 1 is an elevational view, partly in section, showing my improved hat form adjusted to the smallest size.

Fig. 2 is a similar view showing the form adjusted to a larger size;

Fig. 3 is a fragmentary sectional view taken along the line 3—3 of Fig. 1;

Fig. 4 is a fragmentary sectional view taken along the line 4—4 of Fig. 2;

Figs. 5, 6 and 7 show details of a size indicating mechanism employed with the form;

Fig. 8 is an enlarged perspective view of one of the expandable members;

Fig. 9 is a perspective view of one of the members employed in the expansive mechanism;

Fig. 10 is a fragmentary view illustrating one manner in which the expansion members may be modified; and

Fig. 11 is a sectional view showing a modified form in which the frame is not adjustable.

In general my invention consists in the provision of a rubber form designed readily to receive pins used for pinning ornaments to the hat

body, but having a surface over which a needle point can be moved readily without stitching the hat onto the form. This rubber body is preferably made hollow with a separate under-frame which may be made of wood, metal, cork, a molding compound, or other suitable forming material. In a preferred form of the invention, this frame work is made adjustable, whereby the hat form as a body may be adjusted to any suitable size and whereby only a single form may be necessary for producing a large number of head sizes.

Referring now to the drawing, I provide a hat shaped hollow structure 10, preferably made of rubber and having a tough outer layer 11 with a softer underlayer for receiving the pins, the outer layer being skin-like in texture and relatively dense, so that the needle if passed along at an acute angle to the surface will not readily penetrate it. When a sharp instrument such as a pin, however, is pushed in at an obtuse angle to the surface, that is substantially at right angles to the plane of the surface, it will readily enter and be held so as to attach an ornament firmly in position. Although only a single inner layer will produce relatively good results, I preferably use two inner layers 12 and 13, the layer 12 being slightly less dense than the layer 11, and the layer 13 having still less density. In the preferred form, the layer 12 is made of quite dense sponge rubber, while the layer 13 is considerably more porous and formed of normally soft sponge rubber. The inside of the layer 13, that is the surface thereof in contact with the frame, is, of course, finished with a very thin skin, as is usual in sponge rubber articles.

The frame work comprises a plurality of adjustable members 14 which together have the general shape of the interior of the rubber form, and the expanding member 16 which co-operates with the members 14 to move them radially outwardly and increase the size of the frame. The outer form, being of rubber, stretches as the frame is expanded.

A plate 17, forming a part of the frame, closes the form and has a screw 18 threaded onto the expanding member 16. As the drawing shows, the member 16 is provided with ribs 16a and the adjustable members with slots into which the ribs extend. The contacting surfaces between the member 16 and members 14 is such that when the member 16 is drawn toward the plate 17, the members 14 are caused to expand. Figs. 2 and 4 show the position of the frame after expansion, as contrasted with Figs. 1 and 3, which show the frame unexpanded.

In order to avoid a formation of a relatively large unsupporting area at the crown of the form when it is expanded, I provide a cap or plate 19 having a portion coinciding with the normal contour of the form and cross members 19a fitting down between the members 14 so as to hold the cap in position. This member 19 is preferably formed of relatively light sheet metal.

I may construct the device of my invention without employing specific means for determining the size thereof, but depending solely on measuring the form to determine the size thereof. The sizes of women's hats are usually figured in inches and fractions thereof. I provide means for indicating the hat size directly so that at all times that the form is in use, the size to which it is adjusted can be determined by merely glancing at the indicator. Referring now to Figs. 5, 6, and 7, I provide a groove 21 in the plate 17 with an aperture 22 coinciding with the groove and running entirely through the plate. A slide 23 supported in the groove is adjustable therealong and is provided with indicating characters 24 visible through the aperture 22 to show the size to which the form is adjusted. For moving the slide, I provide a pair of members 26 and 27, hinged together at the apex 28, with one member hinged to a cross-piece 29 carried by the plate and the other member hinged to the slide 23 at 31. The two members 26 and 27 are normally pulled toward each other by a resilient member 32, in the present case shown as a semi-soft rubber band. A second cross piece 33 limits the movement imparted to the members by the resilient member 32. The two cross-pieces 29 and 33 in the embodiment shown also function to hold the slide 23 in the groove, but other provisions for accomplishing the same results can, of course, be employed.

Since the vertical position of the expanding member 16 determines the degree of expansion of the frame, I employ the position of this member for determining the head size. Accordingly, I provide means in the form of a cam 34 for engaging the apex 28 of the triangle formed by the two members 26 and 27. Since the movement imparted to the slide 23 is not directly proportional to the vertical movement imparted to the apex of the two members, provisions for compensating for this difference must be made. I accomplish this as indicated in Fig. 6 by providing a curve of the cam 34 calculated to cause the slide 23 to move a distance directly proportional to the vertical distance moved by the cam. I might, of course, secure the same result by graduating the numerals 24 in accordance with the movement imparted to the slide, but I have found that it is more desirable to have a uniform scale on the slide.

Fig. 10 shows a modification in which the adjustable members 114 are formed with interlocking edges 114b. This overlapping occurs where the two members meet just under the rubber form. When these members meet in a straight line and are expanded as indicated in Fig. 4, there is a slot formed between them which may reach considerable proportions when the form is gradually expanded. Under these conditions, the interlocking portions 114b serve substantially the same purpose as the cap 19 shown in the main figures. For most purposes, extreme expansion of the form will not be required and this overlapping or interlocking of the members 14 will not be required.

Since it becomes necessary at times to remove the outer form, I provide means for holding the

inner frame together when it is not supported by the rubber outer form. To this end, I provide an annular groove 35 around the expandable members 14 (Fig. 8) in which groove a relatively large elastic band 36 is placed. This band 5 expands as the frame expands and contracts as the frame contracts. Being inset in the annular groove, it will not affect the contour in any way.

The manner in which the form is used in general should be understandable from the preceding description. When it is used in the ordinary hat shop for manufacturing purposes, the expansion device may or may not be employed, depending upon the size of the shop, the number 15 of forms normally used and other circumstances. It will be apparent that a solid frame may be used and a rubber form pulled over the frame to give the proper head size. The rubber form would then be used until it was worn out, after 20 which it can be stripped off the frame and another form applied thereover. In a relatively smaller shop, it may be desirable to use the expanding feature on all or some of the forms. When the expanding feature is used, it is adjusted to the proper head size and may be used in exactly the same way that it would be used if the frame were non-adjustable. It will be understood, however, that independent of the size of the shop, it may be desired to use the expanding feature even though it will not be utilized part of the time.

The expanding feature is also of advantage when it is necessary to stretch the hat. It may have a slightly different contour depending upon 35 the shape of the hat and may, of course, also be shaped to fit a man's hat and may be used for shaping, blocking, stretching and the like.

I have referred to the outer form or shell as being made of rubber. This is the material 40 which I prefer to use. It will be understood, however, that any elastic moldable material capable of being treated in substantially the same way as rubber can be employed. Such a material is built up to provide a structure which 45 will readily receive a pin but which will have an outer surface of such a degree of smoothness and density that a needle coming in contact with it at an acute angle, as in sewing, will not readily penetrate it. Various rubber-like gums, 50 such as gutta-percha, balata, and similar substances, can be used to give somewhat the same results. I may, however, employ more than one material, for example, I may provide a double layer of sponge rubber, as shown, while the 55 outer layer may comprise a relatively very thin coating of gutta-percha, balata, or a mixture of gutta-percha and balata, using diluents, plasticizing agents and other accessories to obtain the 60 proper characteristics of these materials as is well known in the art.

I have not referred to material employed in the frame, but it will be obvious that any suitable material, preferably light in weight, may be used. Material should be employed, however, which 65 will permit relatively easy sliding movement between the parts. Very light metal, such as aluminum and magnesium alloys may be used, wood or several different types of molding compounds.

In Fig. 11, I show the outer rubber form attached to an inner frame 36 which is not adjustable and which may be of any suitable material as, for example, a molding compound, light weight metal, wood, or the like. This form shows a socket 70

37 which is adapted to fit over any suitable support for holding the form during the time that a hat is being made thereon. The numeral 10 is employed as in the main figures to indicate the outer laminated structure.

5 I have described my invention in detail to permit those skilled in the art to practice the same, but it is obvious that I am not restricted to the particular forms shown, the invention being limited by the scope of the appended claims.

10 What I claim as new and desire to protect by Letters Patent of the United States is:

15 1. A hat form having an outer portion comprising a layer of sponge rubber and an outer skin-like layer of relatively denser rubber, whereby pins are readily inserted therein but a surface is provided over which a needle may be passed as in sewing.

20 2. A hat form having an outer portion comprising a layer of sponge rubber, a superposed relatively thinner layer of sponge rubber having a density greater than said first layer, and an outer skin-like layer of still denser rubber.

25 3. A hat form having an outer portion formed of rubberlike moldable material, said rubberlike moldable material having a density to permit a pin readily to be inserted therein, and having a relatively smooth skin-like dense exterior surface whereby when a needle comes in contact therewith at a relatively acute angle the needle will not penetrate said surface.

30 4. A hat form as defined in claim 3, wherein said outer portion comprises a layer of sponge-like material superposed by a skin-like layer of relatively dense material.

35 5. A hat form comprising an outer shell of elastic moldable material, said shell having an inner layer of sponge rubber and a relatively thin imperforate outside layer of dense elastic material bonded to the sponge rubber, an inner frame for supporting said outer shell, and means for expanding the inner frame to change the size of the shell.

40 6. A hat form comprising an outer shell of elastic moldable material conforming in size and shape generally to the crown of a hat and formed of sponge rubber covered with an outer skinlike layer of dense elastic rubber and an inner expandable frame comprising a plurality of adjustable members, an expanding member disposed within the adjustable members, contacting surfaces being provided between the adjustable members and the expanding member shaped to have a wedge action and means for moving said expanding member to change the radial position of the adjustable members through said wedge action.

45 7. A hat form comprising an elastic shell formed of moldable material, said shell having in general the size and shape of a hat crown, a frame comprising a plurality of adjustable members in contact with the shell, a cone-like expanding member of generally oval cross section, a cover plate, and a screw journaled in the cover plate and threaded into the cone member for drawing the cone-member toward the cover plate to expand the adjustable members.

50 8. A hat form comprising an outer shell of elastic material and an inner frame for supporting said outer shell, said outer shell comprising a body of rubber in the form of layers including an inner layer of sponge rubber, a superposed layer of relatively denser sponge rubber and an outer skinlike layer of relatively dense rubber.

55 9. A hat form comprising an outer shell conforming in general to the size and shape of a hat

5 crown, said shell having a very thin outer layer of relatively dense moldable material, an inner layer of slightly less dense moldable material, and a second innermost layer formed of still less dense moldable material, said layers bonded together to form a single piece shell, and an inner frame supporting said shell.

10 10. A hat form comprising an outer shell of elastic material having substantially the size and shape of a hat crown, and a supporting expandable frame, said frame comprising a plurality of outer adjustable members, and an inner expanding member of generally oval cross section, the adjustable members and expanding members having co-operating surfaces whereby the expanding member when moved axially has a wedgelike action to expand said adjustable members radially, and means for imparting axial movement to said expanding member.

15 11. A hat form comprising a shell of elastic material having substantially the size and shape of a hat crown, an inner supporting frame comprising a plurality of radially disposed adjustable members engaging the shell and having slanting inner surfaces, an inverted cone-like expanding member of generally oval cross section with outer slanting surfaces engaging the slanting surfaces of the adjustable members, a cover plate closing the shell and on which the adjustable members rest, a screw journaled in the cover plate and threaded into the expanding member, and means for turning the screw to draw the expanding member axially and downwardly toward the cover plate to expand the adjustable frame members radially.

20 12. The combination defined in claim 11, including a crown member slidably supported above the adjustable members to maintain a support for the shell at the top thereof when the adjustable members are expanded, said crown member being lifted up slightly when the adjustable members expand.

25 13. The combination defined in claim 11, including a slide supported on the inside of the cover plate and having a scale readable through an aperture in said cover plate, and a connection between said slide and expanding member for transferring vertical movement of the adjustable member into sliding movement of the slide whereby a head size to which the form is adjusted may be read directly from the scale on said slide.

30 14. A hat form comprising an elastic shell formed of rubberlike material, said shell having in general the size and shape of a hat crown, a frame comprising a plurality of adjustable members in contact with the shell, a conelike expanding member, a cover plate on which the adjustable members slidably engage, means for drawing the cone member toward the cover plate to expand the adjustable members, and means carried by the cover plate and operable by the movement of the cone member to indicate the degree of expansion of said adjustable members.

35 15. A hat form comprising an elastic shell formed of rubberlike material, said shell having in general the size and shape of a hat crown, a frame comprising a plurality of adjustable members in contact with the shell, a conelike expanding member, a cover plate, means for drawing the cone member toward the cover plate to expand the adjustable members, and means operable by the movement of the cone member to indicate the degree of expansion of said expandable members, said means including a movable member sup-

- ported on the plate provided with indicia visible through an aperture in said plate, and means operated by the movement of the cone member for moving said movable member.
- 5 16. A hat form comprising an elastic shell formed of rubberlike material, said shell having in general the size and shape of a hat crown, a frame comprising a plurality of adjustable members in contact with the shell, a conelike expanding member, a cover plate, means for drawing the cone member toward the cover plate to expand the adjustable members, means operable by the movement of the cone member to indicate the degree of expansion of said adjustable members, 10 said means comprising a slide supported on the interior of the plate and having indicia visible through an aperture in the plate, a pair of levers pivoted together to form a hinge, the end of one lever pivoted on the plate and the end of 15 other lever pivoted on said slide, and means on the cone member for engaging the hinge between the levers to move said slide as said cone member is moved.
- 20 17. A hat form comprising an elastic shell formed of rubberlike material, said shell having in general the size and shape of a hat crown, a frame comprising a plurality of adjustable members in contact with the shell, a conelike expanding member, a cover plate, means for drawing the cone member toward the cover plate to expand the adjustable members, means operable by the movement of the cone member to indicate the degree of expansion of said adjustable members, said means comprising a slide supported on the interior of the plate and having indicia visible through an aperture in the plate, a pair of 25 levers pivoted together to form a hinge, the end of one lever pivoted on the plate and the end of other lever pivoted on said slide, and a cam 30 carried by the cone member for engaging the hinge between the levers whereby movement of the cone is effective to move said slide, said cam shaped to compensate for the changing angle of said lever members whereby said slide has a movement directly proportional to the movement of the cone member. 5
18. A hat form comprising an outer shell of rubber-like material, having in general the size and shape of a complete hat crown, a supporting plural part frame within the shell including a plurality of adjustable members in contact with the shell and having inner surfaces slanting downwardly and inwardly, and an inverted cone-like expanding member of generally oval cross section engaging said inner surfaces to expand said members proportionally whereby the shape of the shell will remain substantially the same at all size adjustments, and means for drawing said expanding member downwardly. 10
19. A hat form comprising a closed outer shell of rubberlike material, having in general the size and shape of a complete hat crown, a supporting plural part frame within the shell including a plurality of adjustable members in contact with the shell and having inner surfaces slanting downwardly and inwardly over a portion thereof, an inverted cone-like expanding member of generally oval cross section engaging said slanting surfaces to expand said members proportionally to the shape of the hat whereby the shape 25 of the shell will remain substantially the same at all size adjustments, guide means between the adjustable members and expanding member to maintain the same relative position between them, a cover plate over the base of the shell to close the same, and a screw journaled in the cover plate and threaded into the expanding member to draw said expanding member downwardly to move said adjustable members outwardly. 30
